LIQUID METERING DEVICE

Thomas Arthur Fee, Jr., Vancouver, British Columbia, Canada, assignor to Gasoline Energy Distributors Limited, Vancouver, British Columbia, a corporation of British Columbia

Application April 26, 1933, Serial No. 668,024

10 Claims. (Cl. 221—100)

My invention relates to a liquid metering device. More particularly, my invention relates to a liquid metering device which takes into consideration the variations induced in the liquid by a 5 change of temperature.

For purposes of illustration and definiteness of disclosure, I will set forth my invention as applied to the metering devices for dispensing gasoline line as the fuel for internal combustion engines. 10 But it is to be understood that my invention is not to be restricted to any such specific use, but applies to devices where like conditions and like problems are involved. The law defining the gallon of gasoline differs in different countries. 15 In the United States, it is understood, it is that volume of gasoline occupying 231 cubic inches at 60° F. and 760 m. m. pressure, and in the Dominion of Canada as that volume of gasoline at a certain temperature and at a certain barometric pressure which will balance a certain weight. 20

Obviously, when the temperature is higher than said certain temperature, the gasoline in the visible metering cylinders, or glass bowls, expands and flows over and back through the return pipe. 25 This pipe, as presently commonly designed, and used, it will be understood, is at a fixed elevation, and the top is fixed for metering a given number of gallons, usually ten. Under such circumstances, it is obvious that the purchaser of the 30 ten gallons expanded by the higher temperature, does not obtain the amount of fuel that the law says shall equal ten gallons. In other words, he does not receive the full measure for which he paid. Accordingly, serious objection obtains to the present metering devices. Again, a gauge is 35 ordinarily provided marked from zero to ten with markers in between for each level for the gasoline to register the number of units of gasoline present for that level. The gasoline, when pumped into the glass bowl, may be immediately withdrawn, and therefore, any device which will take into consideration the variation in volume, due to change in temperature, must be of a construction which will register the change promptly. 40 That is, by the time the glass bowl is pumped to capacity, and the gasoline has settled down to the level of the top of the withdrawal pipe, then the metering means must have readjusted itself to the temperature change to determine the proper quantity of gasoline to be dispensed as a gallon. 45 The layer of gasoline lying between the mark for one gallon and two gallons may be of a different height than the layer of gasoline lying between the marker seven and the marker eight. 50 It is a primary purpose of my invention to pro-

vide a liquid metering device having an automatically expandible and contractile over-flow return pipe, said pipe being thermostatically responsive to the temperature of the liquid being metered, so as to accurately take into account the variations in volume, due to the variations in temperature, and to do this so rapidly that no delay in dispensing is necessary. 5

Further, it is my object to provide a thermostatic means for controlling the liquid level in a 10 liquid metering reservoir, which means is characterized both by its rapidity of response to changes in temperature of the liquid being metered and the force or power developed in responding. 15

Furthermore, I purpose providing a thermostatically, automatically adjustable overflow-return pipe provided with adjustable volume markers, which markers do not interfere with the registering of the change of temperature of the gasoline 20 throughout all parts of the length of the said thermostatic means. 25

Also, it is a primary purpose of my invention to provide a registering means which will provide for automatically adding together the accumulated expansion or contraction of all of the varying layers of gasoline lying between the various markers. 30

A further object of my invention is to provide an improvement which (a) will render present dispensing equipment accurate, (b) will involve little alteration of said equipment, and (c) will be capable of substitution with a minimum of expense for a precision instrument. 35

The above mentioned general objects of my invention, together with others inherent in the same, are attained by the device illustrated in the following drawings, the same being preferred exemplary forms of embodiment of my invention, throughout which drawings like reference numerals indicate like parts: 40

Figure 1 is a view in side elevation of a gasoline metering reservoir part of a gasoline pump of the visible bowl type, the overflow-return pipe of which reservoir embodies my invention; 45

Fig. 2 is a fragmentary view in longitudinal section of the thermostatically automatically adjustable overflow-return pipe;

Fig. 3 is a top view of said thermostatically adjustable overflow-return pipe; 50

- Fig. 11 is a view in vertical section of another modified form of a thermostatically, automatically adjustable overflow-return pipe;
- Fig. 12 is a view in vertical section of another modified form of a thermostatic means controlling the liquid level in a metering device;
- Fig. 13 is a plan view of one of the members of the modified form of thermostatic means shown in Fig. 12;
- Fig. 14 is a view in vertical section of still another modified form of a thermostatically, automatically adjustable overflow-return pipe means;
- Fig. 15 is a view on dotted line 15—15 of Fig. 14.
- Fig. 16 is a plan view of a thermostatic means having a modified form of guide-support means, i. e., rods;
- Fig. 17 is a fragmentary view of a modified form of an overflow-return pipe embodying my invention, centrally located with respect to the reservoir;
- Fig. 18 is a plan view in reduced scale of the modified form shown in Fig. 17; and
- Fig. 19 is a view in longitudinal section of another modified form of a thermostatic element embodying my invention.
- A thermostatic member or element, of suitable height to meter usually ten gallons, is preferably formed of two concentrically spaced sylphon tubes 15 and 16, closed at the top and bottom, so that an attenuated chamber 17 is formed therebetween. Preferably liquid of the character to be metered, gasoline in present instance, is provided in said chamber through port 18, (Fig. 3), while port 19 serves as an air vent, and then said ports are sealed when said chamber is filled. The gasoline may be placed in said chamber at a temperature lower than that at which the gasoline is normally dispersed, so that the sylphon tubes are placed under pressure. This gasoline may also be introduced with a barometric pressure corresponding substantially to that of the district of use.
- The thermostatic member thus made up ordinarily will be flexible, so that a guide or vertical supporting member, such as slotted pipe 20 is necessary or at least desirable. Pipe 20 is secured into the fitting 21 in the bottom plate 22 of the reservoir 23 and made fast in the top plate 24 of said reservoir 23 by nut 25. Gaskets 26 and 27, and nut 28, together with fitting 21 render easy the substitution of slotted pipe 20 in place of the regular return pipe, which is of a slightly larger diameter than pipe 20. Of course, this consideration is only important where the invention is to be installed in metering devices already manufactured.
- A marker 29 for "10" is mounted on the bottom of the sylphon thermostatic member 15. A

marker 30 for "9" may be adjustably secured to said thermostatic member as follows: A split-ring marker mounting means 31 has a concave bearing 32 adapted to fit over a fold 33 of the sylphon 15 at the approximate elevation of the level of the top of the gallon immediately above marker 29. Lock rings 34 and 35 secure the edge portions of the marker 30 therebetween at the precise desired level above marker 10 to represent one gallon. It will be noted that the adjustable markers allow free access of the gasoline to the sylphon folds. The other markers 36, 37, 38, 39, 40, 41, 42 and 43 for "8", "7", "6", "5", "4", "3", "2", and "1", are likewise adjustably secured to the thermostatic sylphon 15. The top marker 44 for "0" is preferably secured to the top of the sylphon thermostatic element formed by the tubes 15 and 16. The distance between the markers 29 and 44 is such as to represent ten true or full measure gallons. It will be understood that the glass bowl 23 may vary in diameter, and accordingly the markers 29, 30, and 36 to 44 must be adjusted to represent accurately a true gallon unit between each two adjustably disposed markers. The lock rings 34 and 35 on split ring 31 provide for adjustably locating the said markers. Ports 45 in pipe guide 20 provide for the escape of the gasoline into the guide pipe 20 as do slots 46. Intermediate slots 47 may be provided. Electric light means 48 and 49 supply light so that the true level of the gasoline may be observed in the night time.

Inlet pipe 50, having the usual deflecting hood 51, provides for admission of the gasoline to the metering reservoir within the bowl 23, and the usual outlet or withdrawal pipe 52 is provided.

In the modified form of my invention, as shown in Fig. 8, instead of having a thermostatic member with a chamber 17 extending from the bottom to the top of the thermostatic member, separate 40 and individual thermostatic units 53 may be formed of a length equal to the distance between each of the markers 54, 55, 56, 57, 58, 59, 60, 61, 62, 63, and 64. These markers may be in all respects similar in construction to markers 29, 30, and 36 to 44, inclusive. This form of construction manifestly confines the expansion effect to the layer occupied by a specific gallon, but all these are added together to elevate the top to the desired level, and the intermediate markers 50 are elevated to indicate the required level.

In the modified form of the top portion shown in Fig. 10, the guide means do not extend through to the top plate 24. In this form a slot 65 is provided in the top portion of the guide pipe 66. This form of the device is preferably provided with a depending sleeve member 67 secured to the inner edge of the top closing means 68 of the sylphon tubes 69 and 70. This sleeve member 67 may extend to such a point above the bottom plate as will in nowise interfere with the contraction of the thermostatic unit formed by the sylphon tubes 69 and 70. This sleeve 67 provides against undue wear against the guide pipe 66, and is obviously applicable to other forms shown herein.

In the modified form of the device shown in Fig. 11, a thermostatic element 71 is comprised of a single sylphon tube 72 of relatively small diameter to form a confined chamber 73 which is filled with gasoline. The smallness of diameter provides a column which will respond fairly promptly to changes in temperature of the contacting medium. A second thermostatic element 74 is formed precisely like 71. These two ther-

mostatic elements 71 and 74 are joined by a bar 75 having an annular ring in the center 76 which engages an overflow-return pipe 77 of sylphon construction. Adjustable markers 78, 79, and 80 are secured to thermostatic member 74, while similar markers 81, 82, and 83 are secured to thermostatic element 71 on the opposite side. Obviously, the level of the top of pipe 77 will be determined by the height of the thermostatic units 71 and 74.

In the modified form shown in Fig. 12, a thermostatic element 84 is formed of a plurality of thermostatic units 85 which comprise two superimposed metal bands, each having a different coefficient of expansion, the inner metal band 86 having a greater coefficient of expansion than the outer metal band 87. The peripheral face of these units is concave as at 88. These units 85 are fastened together at their joining edges 89 to form a tube constituting the thermostatic element 84, the axial passageway 116 forming an overflow-return pipe. Suitable guide means may also be employed.

In the modified form shown in Fig. 14, a thermostatic element 90 is formed of a plurality of thermostatic units 91 arranged in serpentine form, each unit comprising two strips of metal having different coefficients of expansion, 92 being the metal of the higher coefficient of expansion, and 93 being the metal of less coefficient of expansion. These thermostatic units 91 are secured along their end portions at 94. The thermostatic element 90 is disposed in a casing 95 having perforations 96,—casing 95 serving as a guide supporting member. A second thermostatic element 97 is provided on the opposite side of an overflow-return pipe 98 of sylphon construction. This pipe 98 is secured to a ring 99 carried by bar 100 extending from thermostatic element 90 to thermostatic element 97. Likewise, in this instance, the level of the top of the overflow-return pipe 98, will be regulated by the thermostatic elements or means 90 and 97.

In the modified form shown in Fig. 16, instead of a guide supporting pipe 20 being provided, the three rods 101 are disposed in the angular spaced relation of 120°.

In the modified form shown in Fig. 17, the thermostatic, automatically adjustable overflow-return pipe 102 is located in the axial center of the metering reservoir. A marker mounting means 103, with a concave bearing 104 to engage a sylphon fold 105, is also here provided. Split ring members 106 having flanges 107 are held in gripping relation to marker mounting means 103 by means of set screws 108. On rings 106 are marker rods 109 having thereon a telescopingly mounting member 110, member 110 bearing marker number plate 111. The marker bearing plate 111 is of convex form on its outer face to conform to the curvature of the glass bowl 23 of the reservoir to form a bearing therewith, being yieldingly held by spring 112. In this form the glass bowl 23 functions as a supporting member for the thermostatically, automatically adjustable overflow-return pipe 102.

In the modified forms shown in Figs. 11, 14, 17, and 18, double marker means are shown, so that on two sides of the bowl 23, the gasoline level is indicated.

In the modified form of thermostatic element shown in Fig. 19, the sylphon tubes 113 and 114 have their folds respectively registering and touching, so that the parts of this thermostatic element of this form will be characterized by be-

ing largely mutually self supporting, and the element as a whole will possess in and of itself considerable longitudinal stiffness. Since the folds of each tube only touch tangentially, the pressure, developed due to expansion, will be communicated to the top closing means 115 of the tubes.

The mode of operation of the device embodying my invention is as follows:

In the above description, the mode of operation is set forth to a large degree. In general, it will be seen that my invention is characterized in providing a thermostatically, automatically, adjustable overflow-return pipe, and various methods of constructing this pipe are illustrated.

By forming the thermostatic element of two 15 concentrically disposed sylphon tubes 15 and 16 to provide a chamber 17 therebetween, it is manifest that an attenuated liquid confining chamber is provided. When this is filled with gasoline or a liquid corresponding to that being metered, it 20 is manifest that this column will be quickly effected by any change of temperature of the liquid contacting the outer sylphon tube 15. This change in temperature will be promptly transmitted to the column, and the expansion force of 25 this column is longitudinally directed. It is manifest that the thermostatic element has its axially disposed passageway forming a return pipe. The expansion of the column thus developed by increase in temperature, will be characterized by being relatively powerful and will promptly cause the pipe of sylphon construction to lengthen to compensate for the expansion due to the increase in temperature. The horizontally disposed annular ribs of the sylphon tubes 35 15 and 16 prevent sidewise bulging of the thermostatic element. Furthermore, the guide means 20, or the rods 101 also assist in preventing the sylphon tubes from being inwardly bulged, and the split rings 31 with the lock rings 34 also assist in preventing the sylphon tubes from being outwardly bulged.

Thus my invention provides for an automatically contractile and expansible overflow return pipe, the top or the liquid level determining 45 lip of which will be at that level determined by the temperature of the liquid being metered. When the temperature is such that the gasoline, or other liquid, particularly such other liquids whose volumes are readily subject to 50 changes in temperature, has expanded so as to occupy more space, then the top of the overflow-return pipe is automatically, thermostatically raised to a higher level to accurately compensate for said increased volume, and the amount 55 of gasoline overflowing and returning to the reservoir beneath the ground is proportionately lessened. Thus, the device operates with precision to automatically give accurate gallon measurement for varying temperatures, without any special attention or increased operations, on the part of either the operator or the customer, over that commonly required with present devices. It will be understood that the gasoline is pumped from the reservoir in the 60 ground into reservoir 23 through inlet pipe 50, and so much of the gasoline as is at a level above the top of the overflow return pipe, flows back to the reservoir in the ground. Hence, it will be manifest how important it is to accurately 65 control the level of the top of the overflow pipe.

If desired, regard may be had to the particular elevation above sea level at which the device is to function, and the liquid supplied 75

to the chamber 17 of the thermostatic element may be introduced at a barometric pressure corresponding substantially to that of the district where the same is to be used.

5. Preferably the liquid supplied to the chamber 17 of the thermostatic element is of the same character as that of the liquid being metered. In this wise the thermostatic means will be characterized by having such physical 10 properties as the coefficient of expansion corresponding direct with that of the liquid being metered. However, it is to be understood that another liquid or fluid whose physical properties, as respects its coefficient of expansion, corresponds to the liquid being metered, may be 15 substituted as an equivalent.

It is obvious that the thermostatic element embodying my invention is provided with a surface exposed to the liquid being metered from 20 top to bottom, so that all transverse layers of gasoline have their due effect upon the thermostatic element, the gasoline having free access rearwardly of the marker mounting means.

The various features involved in my invention, 25 thus all cooperate to provide an instrument characterized by its high degree of precision and accuracy.

Obviously, changes may be made in the forms, dimensions and arrangement of the parts of my 30 invention, without departing from the principle thereof, the above setting forth only preferred forms of embodiment.

I claim:

1. A liquid metering device embodying a metering reservoir; and an upwardly projecting liquid tight overflow return means having an upper opening in communication with said reservoir and having thermostatically longitudinally contractible and expansible walls below said upper

40 opening, said contractility and expansibility being in magnitudes which accurately compensate for temperature variations in the liquid being metered, whereby the maximum level of liquid and thereby a meterable unit of liquid 45 in said metering reservoir may be accurately varied in response to thermostatic responsive means.

2. A liquid metering device embodying a metering reservoir; an overflow-return means for said reservoir; and a thermostatic element surrounding said overflow-return means, the top of said element forming a liquid escape gate, whereby the level of the liquid in said reservoir is controlled.

3. In a liquid metering device, a metering reservoir; and an upwardly projecting liquid tight overflow return means having an upper opening in communication with said reservoir and having thermostatically longitudinally contractible and expansible walls below said upper opening, whereby the maximum level of liquid and thereby a meterable unit of liquid in said metering reservoir may be varied in response to thermostatic responsive means.

4. In a liquid metering device, a metering reservoir; and a thermostatic element comprising an attenuated annular column of fluid, means for confining said fluid, said fluid having substantially the same coefficient of expansion and contraction as the liquid being metered, the central portion of said thermostatic element functioning as the overflow-return passageway for said reservoir. 5

5. In a liquid metering device, a metering reservoir; and a thermostatic element comprising an attenuated annular column of liquid, means for confining said liquid, said liquid being the same as that being metered, the central portion of said column functioning as the overflow- 10 return passageway for said reservoir. 15

6. In a liquid metering device, a liquid reservoir; and a liquid overflow-return means for said reservoir, which means includes a thermostatic element comprising two concentrically disposed sylphon tubes forming an attenuated fluid confining chamber therebetween, and top and bottom closing means for said chamber. 20

7. In a liquid metering device, a liquid reservoir; a liquid overflow-return means for said reservoir, which means includes a thermostatic element comprising two concentrically disposed sylphon tubes forming an attenuated liquid confining chamber therebetween; top and bottom closing means for said chamber; and liquid in 30 said chamber, which liquid is the same as that being metered.

8. In a liquid metering device, a metering reservoir; a thermostatic element formed by an attenuated annular column of fluid, longitudinally flexible means forming a chamber for said fluid, the central portion of said element functioning as the overflow-return passageway for said reservoir; and a guide member for said thermostatic element. 40

9. In a liquid metering device, a metering reservoir; a thermostatic element formed by an attenuated annular column of fluid, flexible means forming a chamber for said fluid, said fluid having substantially the same coefficient of expansion and contraction as the liquid being metered, the central portion of said column functioning as the overflow-return passageway for said reservoir; and a guide member for said thermostatic element, said member having openings 50 intermediate its length, which openings function as liquid escape passageways. 45

10. In a liquid metering device, a metering reservoir; a thermostatic element formed by an attenuated annular column of fluid, longitudinally flexible means forming a chamber for said fluid, the central portion of said element functioning as the overflow-return passageway for said reservoir; unit marker mounting means operatively disposed at intervals on said thermostatic element; and unit markers adjustably secured on said mounting means. 55 60

THOMAS ARTHUR FEE, JR.
